SAND DISTRIBUTING DEVICE

Waldo N. Dull and Paul B. Mutzfeld, Butler, Ind.

Application April 20, 1935, Serial No. 17,520

7 Claims. (Cl. 275—15)

This invention relates to a means for distributing material in the form of sand, cinders, or other abrasive means on the surface of a road so as to prevent slipping or skidding of vehicles on ice covered or slippery roads.

An object of this invention is to provide an abrasive distributing means which may be detachably mounted on the end gate of a truck or other carrier or vehicle and which is so constructed that abrasive in the form of sand, cinders or the like may be thrown into the device which includes means for spreading the material on the surface of the road in a predetermined quantity and in a predetermined direction.

Another object of this invention is to provide in a sand distributing device, means operable at will for effecting distribution of sand upon a surface of a road either in the front or in the rear of a truck or other vehicle, the device being so constructed that the quantity of material being distributed may be readily controlled.

A further object of this invention is to provide in a device of this character, means for vibrating the hopper in which the abrasive is placed so that the sand or other abrasive will readily flow downwardly notwithstanding the fact that the sand or other abrasive is wet.

The above and various other objects and advantages of this invention will in part be described and in part be understood from the following detail description of the present preferred embodiment, the same being illustrated in the accompanying drawings, wherein:—

Figure 1 is a detail rear elevation partly broken away and in section of a device constructed according to an embodiment of this invention.

Figure 2 is a detail side elevation partly broken away and in section of the device.

Figure 3 is a fragmentary top plan view of the device.

Figure 4 is a sectional view taken on the line 4—4 of Figure 1.

Figure 5 is a sectional view taken on the line 5—5 of Figure 1.

Figure 6 is a sectional view taken on the line 6—6 of Figure 2.

Referring to the drawings, wherein like numerals of reference designate corresponding parts throughout the several views, the numeral 10 designates generally a frame structure provided at the upper end portion thereof with forwardly extending arms 11 having dependent arms 12, secured to the forward ends thereof. These arms 12 are adapted to engage on the inside of an end gate 13, which is secured to a truck or other

vehicle containing sand or the like, and the end gate 13 is adapted to be disposed between the dependent leg or member 12 on the forward side of the frame 10.

The frame 10, as shown in the drawings, has an upper rectangular frame structure 14 and within this upper frame structure 14, a hopper 15 is secured as by a shaft or trunnions 16. The hopper 15 is swingably mounted within the frame 10. The hopper 15, as shown in the drawings has an inclined upper edge portion 17, which is preferably open and so inclined that the sand or like abrasive may be shovelled from the truck body into the open upper end of the hopper. The walls of the hopper converge to a discharge opening or nozzle 18 and a spout 19 is secured to the discharge member 18. A vertically movable valve or plate 20 is carried by the hopper 15 and a valve operating handle 21 extends upwardly of the wall of the hopper 15 so that the opening 20 through the discharge member 18 may be controlled from above the device.

An adjustable nozzle 22 provided with a pair of elongated openings or slots 23, is mounted on pins or supporting members 24, carried by the frame 10 and this nozzle 22 is adjustable within the limits of the lower portion of the frame 10 which, as shown in the drawings, is reduced at the lower end thereof.

A sand distributing member, generally designated as 25, is disposed below the open lower end of the distributing nozzle or member 22 and is mounted on a shaft 26 journalled in the frame 10. This shaft 26 extends vertically through the frame 10 and the distributing member 25 is secured to the lower end of the shaft 26, as by nuts 27 or like fastening devices.

The distributing member 25 is constructed in the form of a disc or plate 28 provided on the upper surface thereof with a plurality of radially arranged plates or fins 29. The upper end of the shaft 26 has a pinion 30 secured thereto and a driving gear 31 is secured to a drive shaft 32 and the gear 31 meshes with the gear or pinion 30. A bell crank 33 is carried by the shaft 32 so that the driving gear 31 may be manually turned. A housing 34 is disposed about the two gears 30 and 31 so that, if desired, these gears may be provided with a lubricant which may be placed within the housing and so that no sand or abrasive thrown into the open upper end of the hopper will interfere with the operation of the gears.

A cam member 35 is secured to the shaft 26 intermediate the ends thereof and a lug 36 is secured to the spout 19 in a position confronting 35

the cam 35. A contractile spring 37 has one end thereof secured to the frame 10 and the other end secured to the spout 19 so as to constantly maintain contact of the lug 36 with the cam 35. By the use of the cam 35 and the lug 36, the entire hopper 15 is vibrated simultaneous with the rotation of the distributing member 25. In this manner when wet sand or like material is placed in the hopper, the material will readily flow downwardly and be discharged into the adjustable distributing nozzle 22.

In the use and operation of this device, the frame 10 is mounted on the end gate 13 or other wall of the truck with the distributing member 25 extending below the body of the vehicle, at either the front or rear thereof. The sand or other abrasive is shovelled or otherwise placed in the upper end of the hopper 15 and this material will then flow downwardly toward the valve 20. This valve 20 may be adjusted to any desired position by means of the operating member 21. Preferably, before the material in the hopper 15 is permitted to be discharged, the distributing nozzle 22 is adjusted on the supporting members 24 so that the material will be thrown out in a horizontal direction either laterally on one side or the other of the vehicle or rearwardly of the vehicle.

When the valve member 20 is moved to the desired open position, the crank 33 is turned and with the turning of this crank 33, the distributing member 25 will be rotated, and simultaneously the cam members 35 and 36 will vibrate the hopper 15, which is swingably mounted on the shaft 16. While I have shown the shaft 26 as being manually rotated through the crank 33 it is, of course, understood that, if desired, the shaft 26 may be rotated by other power means which, if desired, may be connected to the vehicle in any suitable manner.

By means of the swingable distributing nozzle 22, the sand or abrasive material will engage the distributing member 25 on one side or the other of the vertical axis of the shaft 26 or in a position alining with the axis of the shaft 26. In this manner the direction of the throwing or distributing of the material may be selected and controlled at will.

It is, of course, understood that various changes and modifications may be made in the details of construction and design of the above specifically described embodiment of this invention without departing from the spirit thereof, such changes and modifications being restricted only by the scope of the following claims.

We claim:—

1. A distributing means comprising a frame, means for detachably mounting the frame on a support, a hopper mounted in the frame and provided with a lower discharge opening, a valve for said opening, a rotatable distributing member disposed below the discharge opening, means for rotating said member, an adjustable distributing nozzle interposed between the discharge opening and the distributing member to discharge loose material on to the distributing member at a predetermined point, a lug secured to the hopper, and means carried by the rotating means and engaging the lug to vibrate the hopper.

70 2. A distributing means comprising a frame, means for releasably securing the frame to a support, a hopper in the frame provided with a lower discharge opening, a valve for said opening, operating means for the valve, a horizontally rotatable distributing member positioned below the

discharge opening, operating means for said distributing member, an adjustable distributing nozzle interposed between the discharge opening and the distributing member, means for securing said distributing nozzle in adjusted position relative to the distributing member whereby to discharge loose material on to the distributing member at a predetermined point, a lug secured to a side of the hopper and a cam carried by the operating means engageable with the lug to vibrate the 10 hopper.

15 3. A distributing means comprising a frame, means for detachably mounting the frame on a support, a hopper, means for swingably mounting the hopper in the frame, said hopper having a lower discharge opening, a valve for said opening, a rotatable distributing member disposed below the discharge opening, means for rotating the distributing member, a member secured to the side of the hopper and cam means carried by the 20 rotating means and engageable with said latter member to vibrate the hopper coactive with the rotation of the distributing member.

25 4. An abrasive distributing means comprising a frame, a hopper, means for swingably mounting the hopper within the frame, said hopper having a lower discharge opening, a valve for said opening, operating means for the valve, a horizontally disposed distributing member positioned below the discharge opening, operating means for the 30 distributing member, means interposed between the discharge opening and the distributing member for discharging the abrasive on to the distributing member at a predetermined point whereby to discharge the abrasive in a predetermined 35 direction relative to the distributing member and coacting means carried by the rotating means for the distributing member and the hopper to vibrate the hopper coactive with the rotation of the distributing member.

40 5. An abrasive distributing means, comprising a frame, a hopper disposed within the frame and provided with a lower discharge opening, means for swingably mounting the hopper in the frame, a valve for said opening, operating means for the 45 valve, a horizontally rotatable distributing member positioned below the discharge opening, operating means for said distributing member, said operating means including a vertically disposed shaft, a cam on said shaft, a lug carried by the 50 hopper engaging said cam and yieldable means engaging the frame and the hopper to constantly maintain said lug in contact with the cam to vibrate the hopper upon rotation of the shaft.

55 6. An abrasive distributing means comprising a frame, a hopper within the frame provided with a lower discharge opening, a valve for said opening, a horizontally rotatable distributing member disposed in downwardly spaced relation to the discharge opening, a shaft journaled in the frame 60 and secured at one end to said distributing member, means for rotating the shaft, a cam secured to the shaft, a lug secured to the hopper, a spring secured at one end to the frame and at the other end to the hopper to constantly maintain the lug 65 in contact with the cam to vibrate the hopper simultaneous with the rotation of the shaft and means interposed between the discharge opening and the distributing member to selectively discharge the abrasive at a predetermined point in 70 the rotation of the distributing member.

75 7. An abrasive distributing means comprising a frame, a hopper disposed within the frame and provided with a lower discharge opening, means for swingably mounting the hopper in the frame, 75

5 a manually adjustable valve for said opening, a disc disposed in a horizontal position below the discharge opening, blades carried by the disc, a shaft journalled in the frame and secured at one end to the disc and supporting the disc in downwardly spaced relation to the discharge opening whereby the abrasive passing through the discharge opening will gravitatively fall on to the disc, said blades upon rotation of the disc throw-

ing the abrasive outwardly in a horizontal position, adjustable means interposed between the discharge opening and the disc to control the initial point of contact of the abrasive with the disc and means operable upon rotation of the shaft to vibrate the hopper.
